RESILIENT WHEEL

Albert Frederick William Ruske, San Francisco,
Calif.

Application December 2, 1932, Serial No. 645,483

5 Claims. (Cl. 208—181)

My invention relates to improvements in resilient wheels, and it consists of the combinations, constructions and arrangements hereinafter described and claimed.

5 An object of my invention is to provide a resilient wheel which makes use of a live rubber support, the rubber being perforated to give the desired resiliency. With this construction there is no necessity to provide an air-inflated 10 tire for the wheel.

The wheel may be made of various sizes and I show it especially adapted to a roller skate in which the wheel is secured to the skate by a yielding support. The skate is very yielding to the 15 foot where the wheel is connected to the skate by a spring support, and the wheel itself is provided with a resilient support.

Novel means is provided for permitting a slight play between the wheel and the driving member 20 and the hub of the wheel has floating qualities due to the particular construction.

Other objects and advantages will appear in the following specification, and the novel features 25 of the device will be particularly pointed out in the appended claims.

My invention is illustrated in the accompanying drawing forming a part of this application, in which

Figure 1 is a side elevation of a skate showing 30 the wheel operatively applied thereto;

Figure 2 is a front elevation of the skate;

Figure 3 is a side elevation of the wheel with a part of the structure removed;

Figure 4 is a vertical section through the 35 wheel;

Figure 5 shows a part of the wheel structure, and Figure 6 is a section through a part of the device.

In carrying out my invention I provide a skate indicated generally at 1, which has side members 40 2 and 3. These members are provided with front slots 4 and rear slots 5. The front slots 4 are inclined forwardly and upwardly at an angle and receive an axle 6 of the resilient wheel. The slots 45 5 are inclined rearwardly and upwardly at an angle, and also receive the axle 6 of a similar wheel. The axles are grooved at 7 for receiving the ends of a leaf spring 8. The spring is connected to the skate by a bracket 9.

50 The structure is such that the axles 6 move upwardly in the slots 4 and 5 when a person's foot is supported by the skate. The wheels 10 will be described in detail hereinafter. The springs 8 perform the double function of 55 yieldingly connecting the wheels to the skate

and also prevent a lateral movement of the wheels with respect to the skate.

I will now describe the particular construction of the wheels 10. In Figure 3, I show a live rubber support 11 provided with a number of perforations 12 for giving the necessary resiliency to the support. A ring 13 is disposed on the inside of the rubber support and a rim 14 encircles the outer periphery of the support. A solid rubber tire 15 is mounted on the rim 14.

10 Retaining plates 16 and 17 are secured to the sides of the rim 14 by screws 18 or other suitable fastening means. It will be noted that the plates 16 and 17 have central openings 19 and 20 which are larger in diameter than the inner 15 diameter of the ring 13. The ring 13 bears directly upon a hub 21 and when pressure is brought to bear on the hub in supporting a weight, the hub will move the ring 13 downwardly, and if the weight is great enough the 20 hub will ride on the inner peripheries 19 and 20. When the hub 21 rides on the peripheries 19 and 20 the hub is partially supported by the live rubber support 11.

25 In Figure 4, I show additional plates or flanges 22 and 23 which are connected to the hub 21 by screws 21', and are resiliently connected to the plates 16 and 17. In Figure 5, I show the inner face of the plate 22 and it will be noted that this plate has circular recesses 24 which receive a live rubber ring 25, the ring being mounted on a pin 26 which is carried by the plate 22. Figures 4 and 6 show how the plate 16 is provided with a circular recess 27 for receiving the rubber ring 25. In this way the plate 22 30 is connected to the plate 16.

35 It will be noted also from Figure 4 that the plate 23 is connected to the plate 17 by resilient rings 28 that are received in registering recesses in the plates 17 and 23. Pins 29 support the rings 28 and are carried by the plate 23. The rings 28 are disposed 90 degrees around from the rings 25.

40 When the wheel is used as an idler wheel such as when mounted on a roller skate power need not be applied to the outer plates 22 and 23. Should the wheel be used for driving purposes such as a vehicle wheel, power can be applied to the plate 23 for rotating it. The plate 23, hub 21, and plate 22 will rotate as a unit because 45 they are directly connected together. This rotative movement will be imparted to the plates 16 and 17 by the rings 25 and 28. The rings will permit a slight give before the plates 22 and 23 50 will rotate the plates 16 and 17. At the same 55

time the rings 25 and 28 will permit a slight give and allow the hub 21 to move downwardly when supporting a weight, and to be yieldingly carried by the rubber support 11. Should the weight be too great, the hub would be carried by the inner peripheries 19 and 20 of the plates 16 and 17. It will be seen from this construction that a resilient support is provided and this support will not interfere with the driving plate 22 and 23 should a rotative movement be imparted to these plates.

The hub 21 can house the usual braking mechanism if the wheel is used on a vehicle. The hub 21 can also carry the axle 6 as shown in Figure 1 when the wheel is used for supporting a roller skate. The live rubber support 11 is entirely enclosed and is thus protected from exposure and foreign matter. The tire 15 when worn can be renewed and the wheel will therefore last indefinitely.

While I have only shown the preferred form of the invention, it should be understood that various changes or modifications may be made within the scope of the appended claims without departing from the spirit of the invention.

It is obvious that the number of rubber rings 25 carried by the outer plate 22 may be increased over the two shown in Figure 5, and likewise the number of rubber rings 28 carried by the outer plate 23 may also be increased to any desired number.

I claim:

1. A spring wheel comprising a hub having flanges secured thereto, side members abutting the inner surfaces of the flanges and resiliently connected thereto, a live rubber ring disposed between the side members, metal rings contacting with the inner and outer peripheries of the live rubber ring, the inner metal ring contacting with

the hub, and the side members having openings with a larger diameter than the hub, and a solid tire carried by the outer ring.

2. A spring wheel comprising a hub, a road contacting member mounted on the hub and having a circular live rubber portion, side members secured to the member and having openings larger in diameter than the diameter of the hub, whereby the member can move transversely with respect to the hub until the side members contact with the hub.

3. A resilient wheel comprising a hub, a road contacting member mounted on the hub and including a resilient portion for allowing a slight transverse movement between the member and the hub, and means for providing an unyielding connection between the member and the hub after the member has moved transversely through a predetermined distance.

4. A spring wheel comprising a hub, a metal ring mounted on the hub, a resilient central member mounted on the ring, plates disposed at the sides of the central member, flanges integral with the hub and being disposed at the sides of the plates, and resilient connections between the flanges and the plates.

5. A spring wheel comprising a hub, a metal ring mounted on the hub, a resilient central member mounted on the ring, plates disposed at the sides of the central member, flanges integral with the hub and being disposed at the sides of the plates, and resilient connections between the flanges and the plates, said resilient connections comprising resilient rings received in registering circular depressions in the plates and the flanges, said resilient rings being mounted on pins carried by the flanges.

ALBERT FREDERICK WILLIAM RUSKE.
